UNITED STATES PATENT OFFICE.

JESSE ALEXANDER, OF NEW YORK, N. Y.

DESIGN FOR A TYPE-WRITER FRAME.

SPECIFICATION forming part of Design No. 35,318, dated November 26, 1901.

Application filed October 1, 1901. Serial No. 77,252. Term of patent 14 years.

To all whom it may concern:

Be it known that I, JESSE ALEXANDER, a citizen of the United States, and a resident of the city of New York, borough of Manhattan, 5 in the county and State of New York, have invented and produced a new and original Design for a Type-Writer Frame, of which the following is a full, clear, and exact description.

Reference is to be had to the accompanying drawings, forming a part of this specification, in which similar characters of reference indicate corresponding parts in both the figures.

Figure 1 is a perspective view from the 15 front of a type-writer frame, showing my design; and Fig. 2 is a perspective view from the rear.

My design for a type-writer frame consists in the four corner-posts 1, the opposite posts 20 at each end being connected by flat plates 2, which are connected at about the center by a bar 3, a portion of said bar between the ends being raised above the plane of the end plates, the bottoms of end posts and the rear

posts being connected by base-bars 4, on the 25 top of which are bead-like projections 5, the beads extending up the inner edges of the posts. At the upper ends of the rear posts are bracket-like projections 6, and extended forward from the base of the front posts is a 30 frame 7, the upper sides of the end portions thereof being inclined, and the front posts are also connected by a plate 8, having a comb-like lower edge and a semicircular opening at the top.

Having thus described my invention, I 35 claim as new and desire to secure by Letters Patent—

The design for a type-writer frame, as herein shown and described.

In testimony whereof I have signed my name to this specification in the presence of two subscribing witnesses.

JESSE ALEXANDER.
